FOLDER DEVICE

Edward J. Miller, Cleveland, Ohio

Application March 1, 1938, Serial No. 193,298

7 Claims. (Cl. 46—36)

My invention relates to folder devices in which an image or other representation is animated so as to move relative to another image or representation.

5 An object of my invention is to provide a folder device which moves a representation toward and away from another representation.

Another object is to provide a folder device for moving a representation toward and away 10 from, and in a plane substantially with, a second representation.

Another object is to provide a folder device for moving a representation on one side of a 15 second representation, the first representation being also visible from the other side of the second representation.

Another object is to provide a folder device in which a pictorial representation is borne upon 20 a leaf of the folder and a second pictorial representation is borne upon a carrier which moves in a plane substantially parallel to the said leaf.

Another object is to provide a folder device in which a carrier bearing a pictorial representation is swung in an arc relative to a second 25 pictorial representation borne by a leaf of the folder device.

Another object is to provide a folder device in which the leaves swing upon one axis and in which a carrier carried by one of the leaves is 30 swung upon a second axis at an acute angle to the first axis and in which the carrier is moved in a plane substantially parallel to another leaf of the folder device.

Another object is to provide a folder device for 35 animating a pictorial representation in which a portion of the pictorial representation swings in an arc and substantially parallel to a complementary portion of the representation.

Another object is to provide a folder device in 40 which parts of the device swing upon an axis and in which other parts swing upon a pivot point lying upon the said axis.

Another object is to provide a construction for a folder device which has parts movable relative to each other by opening and closing the 45 folder device.

Another object is to provide a folder device having a construction which is economical and simple to produce and which is efficient in operation.

A still further object is to provide a folder device having a plurality of carriers which move relative to a leaf of the folder device and relative to each other.

55 Another object is to provide a folder device

having movable parts which attractively present the animation of objects borne thereon.

Other objects and a fuller understanding of my invention may be had by referring to the following description and claims, taken in conjunction with the accompanying drawings, in which:

Figure 1 is a view of my folder device in closed position with the first leaf on top;

Figure 2 is a view of my folder device half 10 opened up with the raised leaves extending perpendicular to the plane of the drawing;

Figure 3 is a view of my folder device completely opened up and with the leaves lying flat 15 substantially parallel to the plane of the drawing;

Figure 4 is a view looking into the bottom edges of the folder device in the direction of the arrows 4—4 of Figure 3;

Figure 5 is a similar view looking into the bottom edges of the folder device in the direction 20 of the arrows 5—5 of Figure 2;

Figure 6 is a similar view looking at the bottom edges of the folder device in the direction of the arrows 6—6 of Figure 1; and shows the leaves somewhat spread apart for purposes of clarity 25 of illustration;

Figure 7 is a plan view of my folder device in extended position with all of the folded portions spread out in the flat;

Figure 8 is a fragmentary view of the bottom 30 portion of my device showing a slightly different form of construction in which the carrier is pasted or otherwise secured to a leaf of the device;

Figure 9 is a perspective view of my folder device in half open position with the leaves somewhat spread apart for clarity of illustration, the view being somewhat diagrammatical for illustrating the operation of the device;

Figure 10 illustrates a modified form of my folder device in which two carriers are utilized;

Figure 11 illustrates a still further modified form of my device in which two carriers are utilized and which are mounted in different relative positions from that shown in Figure 10; and

Figure 12 is a view somewhat like Figure 7 45 showing the folder device in an extended position, but shows the carrier extending from and carried by a rear leaf of the folder device.

My folder device may be constructed of any sheet material of suitable character. In adaptation for greeting cards, advertising folders, and the like, it is preferably made of a cardboard material usually utilized for cards and folders of this nature, having the required amount of stiffness and flexibility. Thin cardboard or heavy 50

55

paper is the usual material for cards and folders of this kind. The sheet of material may be die cut or cut out in proper outline in any other suitable manner.

- 5 Referring to Figure 7 which shows the sheet of material cut out in proper outline and lying in the flat, the construction and position of the parts is better illustrated. The rectangular sheet shown in Figure 7 is folded or creased along two 10 longitudinal lines at right angles to each other, the crease 19 being disposed in one direction and the crease 20 being disposed in a direction at right angles to the first crease. These two creases, therefore, divide the sheet of material 15 into four segments which form the four leaves 15, 16, 17, and 18. The leaf 17 has an opening 34 cut therethrough. This opening 34 may be a hole cut in the leaf 17 as shown or may be a transparent portion of suitable material which 20 permits visibility through the opening 34. The image 35 is drawn upon or otherwise carried upon the leaf 17. The image 35 may be any representation and is positioned adjacent to, or relative to, the opening 34.
- 25 Along the bottom edge of the leaf 18, there is an appendage portion 22 which has the carrier member 23 extending therefrom. The leaves 15, 16, 17, and 18, the appendage portion 22, and the carrier member 23, are all constructed of the 30 one sheet of material. The crease 21 permits the appendage 22 to be bent back and under the adjacent leaf 16. The crease 24 permits bending or swinging of the carrier member 23 relative to the appendage 22 and leaf 18. By folding 35 the appendage 22 along the crease 21, the appendage 22 is brought up adjacent to and parallel to the leaf 16. This swings the carrier member 23 around so as to be brought up adjacent and parallel to the leaf 17 with its reverse face showing. The image 36 on the carrier member 23 is not shown in the view of Figure 7 as it is face down and is disposed on the opposite side of the carrier member 23, but upon the carrier member 23 being swung up, the said 40 opposite side of the carrier member 23 is directed toward the rear face of leaf 17 and the image 36 faces the same way as the image 35 on the leaf 17.
- 45 A triangular portion is cut out of the sheet of material at its lower edge between lines 25 and 26 which extend from the edge to point 27 on crease 20. Carrier member 23 is not connected to the sheet of material except through crease 24 and appendage 22. It is preferable to cut back leaf 17 along line 26 at a slightly larger angle 50 than is leaf 16 along line 25.
- 55 The sheet of material is folded along the crease 19 so that leaves 15 and 18 are swung down and in position adjacent and substantially parallel to the leaves 16 and 17. The leaves 16 and 17 retain their position shown in Figure 7 and leaves 60 15 and 18 are reversed to be disposed in the rear of leaves 16 and 17 so that the faces of leaves 15 and 18 shown in Figure 7 are directed in the opposite direction. The material connecting leaves 15 and 16 and leaves 17 and 18 along the crease 19 hold leaves 15 and 16 and leaves 17 and 18 in substantially parallel relationship. It 65 is seen that the carrier member 23 is interfitted between the leaves 17 and 18 and is held in a plane substantially parallel to the planes of leaves 17 and 18 which act as guides to hold the carrier member 23 in said position.
- 70 The folder device is next folded along the crease 20 so that the face of leaves 16 and 17 shown in Figure 7 are brought together. Swing-

ing of leaves 16 and 17 relative to each other also swings leaves 15 and 18 which are attached thereto, respectively. In this manner, a folder having four leaves is formed. The leaves are in pairs, leaves 15 and 16 being one pair, and leaves 17 and 18 being the other pair. These pairs of leaves swing upon substantially the same axis formed by the crease 20. When they are in the spread out position shown in Figure 3, leaves 16 and 17 are in front and are referred to as the front leaves, and leaves 15 and 18 are referred to as the rear leaves. The leaves of each pair of leaves are retained in substantially parallel relationship to each other by reason of the connection along the crease 19.

14 The folder device having been folded as described and having the pairs of leaves folded together in closed position, is illustrated in Figure 1. In this view, leaf 15 is the first page of the folder device in book form. Leaf 15 is shown on top of the folder device and the crease 20 is the hinge of the folder device in book form, the crease 20 being along the left hand edge in Figure 1. The carrier member 23 shown in broken lines is positioned between leaves 17 and 18. When in this flat closed position, the carrier member has been folded upon the crease 24. Leaf 17 being cut away along the line 26 accommodates the carrier member 23 so as to permit the carrier member 23 to extend across the corner 30 of the folded folder device between leaf 16 to its position between leaves 17 and 18. The opening 34 shown in broken line is in the leaf 17 and is illustrated to show its relative position to the carrier member 23 when the folder device is in the closed position of Figure 1. The carrier member 23, when the folder device is folded as in Figure 1, is swung back close to the crease 20. The crease 24 acts as an axis upon which the carrier member 23 swings, and the crease 20 acts 40 as an axis upon which the leaves of the folder swing. Point 27 is at the intersection of lines running through these two axes and is the pivot point about which the carrier member 23 swings. The axis along the crease 24 is disposed at an acute angle to the axis formed by the crease 20.

45 Figure 6 is a view looking in the direction of the arrows of 6-6 of Figure 1 and illustrates the positioning of the parts. For purposes of clarity the leaves are somewhat spread apart and may be closer together in actual practice. In this view of Figure 6, it is seen how the carrier member extends across the lower corner of the folder device, by reason of the triangular portion cut away between the lines 25 and 26. At the bottom 55 of the folder device, as shown in Figure 6, the leaves may be spread slightly fan-wise but it may be said that throughout the length of the folder device that the leaves and the carrier member are substantially parallel to each other.

60 Figure 2 is the folder device with leaves 15 and 16 raised perpendicular to the plane of the drawing so that the folder device is half open. The representation 35 on the leaf 17 is in full view. The representation 36 borne upon the carrier member 23 is complementary to the representation 35. The opening 34 permits that part of the representation 36 back of the opening 34 to be visible. It is seen that the carrier member 23 has swung in an arc upon the pivot point 27 down from the position illustrated in Figure 1. The image of the man in the representation 36 has therefore bent slightly toward the image of the women in the representation 35. When the folder device is in the half open position of Fig- 75

ure 2, the carrier member 23 has gone through half of the extent of its movement so that the representation 36 has moved from its most withdrawn position part way toward the representation 35.

Figure 5 being a view looking at the bottom edges of the leaves shown in Figure 2, illustrates the positioning of the leaves and the carrier member. Again it is seen how at the bottom 10 of the folder device, the carrier member 23 cuts across the corner from leaf 16 to its inserted position between leaves 17 and 18.

Figure 3 illustrates the folder device when completely open with leaves 16 and 17 lying flat. The 15 carrier member 23 has moved to its other limit of movement so that the man's head has moved down toward the image of the woman in the representation 35 on leaf 17. The movement of the carrier member 23 is such that it moves in a 20 plane substantially parallel to the plane of leaf 17, it being guided in said substantial plane by the rear leaf 18. During the movement of leaves 15 and 16 upon the axis formed by the crease 20, the carrier member 23 has swung upon the axis 25 formed by the crease 24. Since crease 24 is at an acute angle to crease 20, the two axes are stated to be at an acute angle to each other. Point 27 at the intersection of the two axes is a pivot point about which the carrier member 30 23 swings in its movement. In Figure 3, a part of the carrier member 23 is disclosed as extending across the triangular portion cut off between lines 25 and 26. Upon swinging the pairs of leaves together relative to each other, the process is 35 reversed so that the carrier member 23 swings back in an arc upon the pivot point 27 through the position illustrated in Figure 2 and back into the position illustrated in Figure 1, the other limit of its movement.

Figure 4 illustrates a view looking in the direction of the arrows 4-4 and shows the bottom edges of the folded device when in the opened position. While the leaves are shown closely together in Figure 4 and the leaves shown somewhat spread apart in Figure 3, these slight changes have been made for purposes of clarity of illustration, the relative positioning of the parts being the same.

Figure 9 is a view somewhat diagrammatical 50 in nature for the purpose of illustrating the movement of the parts. Point 27 is at the intersection of the axis formed by the crease 20 and the axis formed by the crease 24. Point 29 at the end of the crease 24 opposite from point 27 moves during the folding and unfolding of the pairs of leaves of the folded device. The path of movement of point 29 forms an arc shown in broken line in Figure 9 and connecting points 30, 29, and 31. When the folding device is closed 60 as illustrated in Figure 1, then point 29 coincides with point 31. During the unfolding of the leaves, point 29 rises in an arc to the point on the arc shown at point 29 in Figure 9. When the folder device has been completely opened to the position shown in Figure 3, then the point 29 moves in an arc down to the position denoted by the reference character 30. During this movement of point 29, the carrier member 23 swings in an arc upon point 27. The swinging of the carrier member 23 upon the axis formed by the crease 24 is therefore translated into a movement substantially parallel to the planes of leaves 17 and 18. This movement of the carrier member 23 changes the relative position of the representation 36 to the opening 34 and varies the 75

degree to which the representation 36 is visible through the opening 34. When point 29 is in its highest position, being that shown in Figure 9, there is a tendency for the lower edge of the leaf 17 to be slightly raised and the flexibility of the sheet material permits some slight bending to prevent any binding of the carrier member 23 upon the leaf 17. When in the closed position, point 29 does not exactly coincide with point 28 as line 26 is cut back slightly more at an angle 10 than line 25 so as to permit more freedom to the carrier member extending between the leaf 16 to the inserted position between leaves 17 and 18.

Figure 8 is a fragmentary view illustrating the different manner of attaching the carrier member 23 to the leaf 16. The carrier member 23 instead of being hingedly connected to the appendage 22 is hingedly connected to a tab portion 37 which is pasted or otherwise suitably secured to the leaf 16. In this form it is not necessary 20 to have the carrier member 23 cut out of the same sheet of material as the leaves of the folder. The carrier member 23 may be separately formed and connected in proper position by pasting or otherwise securing the tab portion 37 to the leaf 25 16. It is preferable to paste the tab portion 37 to the underside of the leaf 16 for purposes of appearance.

In Figure 10, I illustrate a modified form of my holder device in which two carrier members 39 are utilized. The leaf 17 has the opening 34 cut therein, and a representation 38 such as the image of a bird is drawn or otherwise borne upon the leaf 17. A carrier member 39 is carried by the leaf 16. The tab portion 40 of the carrier member 39 is pasted or otherwise secured to the under face of leaf 16 and the carrier member 39 swings upon the axis 24 in the same manner as described for the preferred form illustrated in Figures 1 to 3 inclusive. The representation 40 44 which may be the image of a Spaniel dog as illustrated, is drawn or otherwise borne upon the carrier member 39.

The carrier member 41 having tab portion 42 is also secured to the under face of leaf 16 at the 45 upper edge of leaf 16. Another triangular portion must be cut out of leaves 16 and 17 in the same manner as the triangular portion which was cut out along the bottom edge. The triangular portions upon the upper and lower edges 50 of the folder device shown in Figure 10 are the same and both provide for the extending across of the carrier members 39 and 41 from the leaf 16 to their inserted position between leaves 17 and 18. As the upper edge of the folder device 55 is folded along the crease 19, it is necessary to cut along the crease 19 between lines 25 and 26 in order to complete the triangular cut away portion. In order to prevent binding it is also preferable to cut a slit between points 28 and 52 in 60 order to prevent some slight separation of leaves 17 and 18 during the swinging of the pairs of leaves toward and away from each other. The carrier member 41 similarly swings upon the axis formed by the crease 24 and moves in a plane 65 substantially parallel to the leaves 17 and 18. The carrier member 41 has drawn upon it or otherwise bears the representation 43 which may be an image of a Scotty dog as illustrated in Figure 10. The operation of the carrier members 70 39 and 41 are the same in principle as the operation of carrier member 23 in the preferred form shown in Figures 1 to 3. By swinging the pairs of leaves together into closed position, the image of the Scotty dog on carrier member 41 75

will move down away from the image of the bird and the image of the Spaniel dog on the carrier member 39 will move up towards the image of the bird. Opening up of the folder device reverses this movement so that the Scotty dog moves upward and the Spaniel dog moves downward. The image of the Scotty dog and the image of the Spaniel dog moves in their separate arcs about the pivot point 27. This alternate movement of the images moving in their respective arcs gives the illusion of the dogs alternately jumping up towards the bird.

Figure 11 illustrates still a further modified form of my folder device. The carrier member 49 having the tab portion 48 is secured by pasting or other suitable means to the leaf 16 and the movement of the carrier member 49 relative to the opening 34 is similar to that shown in the preferred form shown in Figures 1 to 3 inclusive. In this modification, shown in Figure 11, there are three pairs of leaves. In addition to leaves 15 and 16 and leaves 17 and 18, there are leaves 45 and 46 which are merely extensions of leaves 17 and 18. Leaves 45 and 46 swing upon an axis formed by the crease 47 and swing in toward and away from leaves 17 and 18 just as do leaves 15 and 16. Leaves 16, 17 and 45 are the front leaves and leaves 15, 18, and 46 are the rear leaves. Crease 19 extends across the sheet of material 30 and connects leaves 45 and 46 in the same manner as it connects the other leaves.

The carrier member 51 having the tab portion 50 is pasted or otherwise suitably secured to leaf 45 and swings upon an axis at an acute angle to the axis formed by the crease 47. The carrier member 51 therefore moves in the plane substantially parallel to the leaves 17 and 18 just as does the carrier member 49. To prevent interference of carrier members 49 and 51 in their movement, the carrier member 51 is positioned to move between the carrier member 49 and leaf 17. When in the open position shown in Figure 11, the carrier member 51 is seen first through the opening 34 and the carrier member 49 is seen just in the rear of the carrier member 51. Both carrier members move in planes substantially parallel to each other. This modification adapts itself to still further changes in animation of objects. Each carrier member swings in separate arcs around its own pivot point 27. A representation may be drawn upon leaf 17, upon carrier member 49, and upon carrier member 51. Different schemes of animation may be utilized so as to give different effects, for example, the representation of a boxer may be carried by one carrier member and the representation of another boxer may be carried by the other carrier member and different movements of the carrier members will give the effect of sparring action by the boxers.

It is apparent in all of these modifications that the direction of the carrier members utilized in any specific case is dependent upon the angularity of the axis upon which the carrier member swings, in relation to the axis upon which the leaves swing. A change in the angle of crease 24 in relationship to crease 28 will vary the nature of the movement of the carrier member. In order to obtain the desired movement of the representation of the carrier member, the desired angularity of the crease 24 is provided.

Various changes and forms may be made as suggested by the illustration shown. For example, carrier member 51 in the view of Figure 11 could be positioned so that tab portion 50 is secured to

the upper edge of the leaf 45 diagonally opposite from tab portion 48. With this change, carrier member 51 would operate in the same manner as carrier member 49 in the folder shown in Figure 10 and its operation relative to carrier member 49 is apparent. The positioning of the carrier members and the angularity of the axis upon which they swing being dependent upon the choice of specific requirement for animation desired.

In Figure 12, there is illustrated a view of my folder device somewhat similar to that shown in Figure 7 with all portions spread flat. This view illustrates that the carrier member may be carried by one of the rear leaves as well as by a front leaf. It is seen that appendage 22 extends from leaf 15, a rear leaf, instead of from leaf 16 as shown in Figure 7. The mounting and operation of the holder device is nevertheless the same, the carrier member 23 extending through the triangular cut away portion formed by lines 25 and 26 to interfit between leaves 17 and 18. Since the front leaf 16 and rear leaf 15 swing together upon the axis relative to leaves 17 and 18, the carrier member may be secured to either leaf 16 or leaf 15. In cases where the carrier member is pasted or otherwise suitably secured to the leaf rather than being integral therewith, it may be secured by pasting or otherwise suitably securing the tab portion attached thereto to the rear leaf as well as the front leaf. In the previous modifications wherein the carrier member was shown as secured to the front leaf, it may be likewise secured to the corresponding rear leaf as the front leaf and corresponding rear leaf swing together upon its axis.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A folder device comprising a sheet creased upon a horizontal median line and then upon a vertical median line to provide two pairs of joined front and rear leaves adapted to swing upon the crease along the vertical median line, said sheet having a triangular open space at an edge thereof, the apex of the said triangular open space being positioned adjacent the crease along said vertical median line, a carrier member having a supporting appendage carried by, and positioned between the front and rear leaves of, a first of said pairs of leaves, said carrier member being extended across said triangular open space and interposed between the front and rear leaves of a second of said pairs of leaves, the carrier member being creased along a line at an acute angle to said vertical median line to cause the carrier member to swing in an arc between the front and rear leaves of said second pair of leaves upon the swinging of a said pair of leaves relative to another said pair of leaves.

2. A folder device comprising a sheet creased upon a horizontal median line and then upon a vertical median line to provide pairs of joined front and rear leaves adapted to rotate upon the axis formed by the crease along the vertical median line, said sheet having a triangular open space at an edge thereof and in adjacent portions of said front leaves at said vertical median line, a carrier member having an end portion carried by, and positioned between the leaves of,

5 a first of said pairs of leaves and having another end portion interposed between and movable substantially parallel to, the leaves of a second of said pairs of leaves, the said carrier member being extended across said triangular open space adjacent to said rear leaves and being creased along a line disposed substantially adjacent to a side of said triangular open space to permit the carrier member to bridge the variable angular 10 space between said front leaves and to swing in an arc between the leaves of said second pair of leaves upon the rotation on said axis of one pair of leaves relative to another pair of leaves.

15 3. A folder device comprising a sheet creased upon a horizontal median line and then upon a vertical median line to provide two pairs of joined front and rear leaves adapted to swing upon the crease along the vertical median line, said sheet having an appendage extending from 20 an edge thereof and folded back upon said sheet and interposed intermediate the front and rear leaves of the first pair of leaves, said appendage having an extending portion adapted to extend to, and interfit between, the leaves of the second 25 pair of leaves, the extending portion being creased along a line disposed at an acute angle to said vertical median line to cause the extending portion to swing in an arc between, and substantially parallel to, the leaves of said second 30 pair of leaves, said sheet being cut away to remove adjoining portions of the front leaves at said vertical median line to permit the said extending portion to bridge the variable angular space between the planes of said pairs of leaves, upon 35 the swinging of one pair relative to the other pair.

40 4. A folder device comprising a sheet creased upon a horizontal median line and then upon a vertical median line to provide two pairs of joined front and rear leaves adapted to swing upon the crease along the vertical median line, said sheet having a triangular open space at an edge thereof, the apex of said triangular open space being positioned adjacent the crease along 45 said vertical median line, a carrier member having a supporting appendage carried by a first of said pairs of leaves, said carrier member being extended across said triangular open space and interposed between the front and rear leaves of a second of said pairs of leaves, the carrier member being creased along a line at an acute angle to said vertical median line to cause the 50 carrier member to swing in an arc between the front and rear leaves of said second pair of leaves upon the swinging of a said pair of leaves relative to another said pair of leaves.

55 5. A folder device comprising a sheet creased upon a horizontal median line and then upon a vertical median line to provide two pairs of joined front and rear leaves adapted to swing upon the crease along the vertical median line, said sheet having an appendage extending from 60 an edge thereof and folded back upon said sheet and interposed intermediate the front and rear

leaves of the first pair of leaves, said appendage having an extending portion adapted to extend to, and interfit between, the leaves of the second pair of leaves, said extending portion being adapted to carry a portion of a representation 5 and the second pair of leaves being adapted to carry a complementary portion of the representation, the front leaf of said second pair of leaves having a transparent portion adapted to disclose the portion of the representation carried by said 10 extending portion, the extending portion being creased along a line disposed at an acute angle to said vertical median line to cause the extending portion to swing in an arc between, and substantially parallel to, the leaves of said second 15 pair of leaves and to vary the relative positions of the complementary portions of said representation, said sheet being cut away to remove adjoining portions of the front leaves at said vertical median line to permit the said extending 20 portion to bridge the variable angular space between the planes of said pairs of leaves, upon the swinging of one pair relative to the other pair.

25 6. A folder device comprising a sheet creased upon a horizontal median line and then upon a vertical median line to provide two pairs of joined front and rear leaves adapted to swing upon the crease along the vertical median line, said sheet having a triangular open space at an 30 edge thereof, a point of the said triangular open space being positioned adjacent the crease along said vertical median line, a carrier member having a supporting appendage carried by a first of said pairs of leaves, said carrier member being extended across said triangular open space and interposed between the front and rear leaves of a second of said pairs of leaves, the carrier member being creased along a line at an acute angle to said vertical median line to cause the 35 carrier member to swing in an arc between the front and rear leaves of said second pair of leaves upon the swinging of a said pair of leaves relative to another said pair of leaves.

40 7. A folder device comprising a sheet creased upon a horizontal median line and then upon a vertical median line to provide two pairs of joined front and rear leaves adapted to swing upon the crease along the vertical median line, said sheet having a triangular open space at an 45 edge thereof, a point of the said triangular open space being positioned adjacent the crease along said vertical median line, a carrier member having a supporting appendage carried by a first of said pairs of leaves, said carrier member having a projecting portion adapted to carry a portion of a representation, said projecting portion being extended across said triangular open space and interposed between the front and rear leaves of a second of said pair of leaves, the front leaf 50 of said second pair of leaves being adapted to carry a complementary portion of said representation and having a cut away portion adapted to disclose the portion of the representation carried by the projecting portion of the carrier member, the carrier member being creased along a line at an acute angle to said vertical median line to cause the carrier member to swing in an arc between the front and rear leaves of said 55 second pair of leaves and to vary the relative positions of the complementary portions of the said representation upon the swinging of a said pair of leaves relative to another said pair of leaves.

60 75 EDWARD J. MILLER. 75
